DESIGN FOR A SERVICE STATION ISLAND OR THE LIKE

James M. Arthur, Evanston, and Charles A. Urbanek, Chicago, Ill., assignors to Standard Oil Company, Chicago, Ill., a corporation of Indiana

Application December 1, 1933, Serial No. 49,922

Term of patent 3½ years

To all whom it may concern:

Be it known that we, JAMES M. ARTHUR and CHARLES A. URBANEK, citizens of the United States, and residents, respectively, of Evanston, in the county of Cook and State of Illinois, and Chicago, in the county of Cook and State of Illinois, have invented a new, original, and ornamental Design for Service Station Island or the like, of which the following is a specification, reference being had to the accompanying drawing, forming part thereof.

We claim:

The ornamental design for a service station island or the like, substantially as shown.

In witness whereof, we have affixed our signatures.

JAMES M. ARTHUR.
CHARLES A. URBANEK.
